By Chas. E. Riordan
Atty.

UNITED STATES PATENT OFFICE.

NELSON S. PECKENS, OF WASHINGTON, DISTRICT OF COLUMBIA, ASSIGNOR OF ONE-THIRD TO PETER M. ULRICH AND ONE-THIRD TO ELMER E. SCOTT, BOTH OF WASHINGTON, DISTRICT OF COLUMBIA.

COVER-FASTENER.

1,323,488.

Specification of Letters Patent.

Patented Dec. 2, 1919.

Application filed March 25, 1919. Serial No. 284,935.

To all whom it may concern:

Be it known that I, NELSON S. PECKENS, a citizen of the United States, and a resident of Washington, in the District of Columbia, 5 have invented certain new and useful Improvements in Cover-Fasteners, of which the following is a specification.

This invention relates to means for fastening covers on receptacles, and is especially 10 designed for securing coffin lids in place so as to make substantially air tight joints with the coffins when the parts are made to properly fit together.

Another object of the invention is to provide a simplified fastener adapted for use on any cover and adapted to not only retain 15 said cover in place on the receptacle against lateral or longitudinal movement but also to forcibly hold the cover down close upon the 20 edge of the receptacle.

Another object is to provide a fastener of this character which when in position is completely concealed.

Other objects will appear as the description proceeds.

The invention will be first hereinafter described in connection with the accompanying drawings, which constitute a part of this specification, and then more specifically defined in the claims at the end of the description.

In the accompanying drawings wherein similar reference characters are used to designate corresponding parts throughout the 35 several views—

Figure 1 is a broken elevation of a portion of a coffin showing the cover retained in place thereon by fastening means constructed and applied according to this invention.

40 Fig. 2 is a sectional view on a larger scale showing the relative positions of the parts of the fastener when the cover is first placed on the receptacle.

Fig. 3 is a plan view of the edge of the receptacle with the spring retaining member attached thereto.

Fig. 4 is a view similar to Fig. 2 showing the positions of the parts of the fasteners after the cover is moved into locked position; and

Fig. 5 is a detailed view of a modified form of headed pin member of the fastener.

In the drawings, 1 designates the receptacle which may be a coffin as shown in Fig.

1 or any other container, and 2 is the cover 55 which may also be of any desired shape to conform to the container or receptacle on which it is used. Any number of the fasteners for securing the cover on the receptacle may be employed, as may be dictated by the 60 requirements of the occasion. One such fastener is sufficient for the purpose of illustration.

Said fastener consists of a headed pin member 3 which may be carried by a plate 4, 65 and secured to one of the parts to be secured together by screws 5, and a spring retaining member 6 which is secured to the other part by screws 7. As illustrated in Fig. 5 the headed pin member may be made 70 in the form of a screw 8 having a flange 9 to fit against the edge of the part to which it is secured in place on the plate 4 of Figs. 1, 2 and 4, as will be readily understood. The head 10 of the pin is sufficiently larger than 75 the shank thereof to afford an effective engagement with the edges of a slot 11 in a spring tongue 12 on the member 6.

The tongue 12 is preferably made integral with a plate portion 13 of the member 6, as 80 shown, and said tongue is housed in a cavity 14 formed in the edge of the receptacle while the plate portion 13 covers said cavity. Said plate has a key slot 15 the enlarged end portion 16 of which is of a size to admit the 85 head 10 of the pin 3, while the body portion of said slot is preferably narrower than said head. The spring tongue also has a key slot 17 which registers with the key slot 15 in

the plate, the enlarged end portion 18 of the slot 17 being directly below the corresponding portion 16 of the slot 15, while the body portion of said slot 17 is substantially co-extensive with the same portion of said slot 15 and narrower than the head of the pin. 90 The tongue is bowed at 22 and extends downwardly from the plate in a curve and near its end is bent slightly upward at 19 where the slot 17 terminates. The bottom 20 of the cavity 14 conforms generally to the shape of the tongue, but there is a sub-cavity 21 in said bottom of greater width than the head 10 of the pin to permit said head to work along the slot 17 below the tongue 12 and to engage the edges of said slot.

105 As shown in Fig. 2, when the pin 3 is first introduced into the enlarged end portions of the key slots in the plate 13 and tongue 12,

the head 10 is positioned below the adjacent upper end portion of the tongue but above the level of the bowed and lower end portions thereof. As the cover is moved to the left in Fig. 2, the head 10 of the pin 3 will rise along the under face of the tongue in the slot 17 therein, and will raise the tongue to the position shown in Fig. 4 where it is placed under tension which serves to hold the cover tightly down on the receptacle. In reaching the extremity of the slot 17 the head of the pin passes the bowed portion 22 of the tongue, so that said bowed portion serves to retain the pin against accidental reverse movement which would disengage it from the tongue, although said pin may, of course, be forcibly moved back over the bowed portion of the tongue when it is desired to remove the cover.

Having thus fully described my invention, what I claim as new and desire to secure by Letters Patent of the United States, is:—

1. A cover fastener comprising a headed pin member, and a spring tongue member, having a key slot to be engaged by the pin, said tongue being normally inclined to the plane of movement of the pin, whereby it is placed under tension when the pin is engaged therewith, and said tongue also having its intermediate portion bowed for retaining the pin in engaged position.

2. The combination with a receptacle and cover, of a fastener comprising a headed pin member secured to one of said parts, and a spring tongue member secured to the other part, there being a cavity in the latter part in which said tongue is housed, said tongue having a key slot to be engaged by the pin, and normally arranged at an incline to the plane of movement of said pin, whereby said tongue is placed under tension when the pin is engaged therewith for holding the cover down tight on the receptacle.

3. The combination with a receptacle and cover, of a fastener comprising a headed pin member secured to one of said parts, and a spring tongue member secured to the other part, there being a cavity in the latter part in which said tongue is housed, said tongue having a key slot to be engaged by the pin and normally arranged at an incline to the plane of movement of said pin, whereby said tongue is placed under tension when the pin is engaged therewith for holding the cover down tight on the receptacle, and

means on said tongue for retaining the pin in engagement therewith against accidental displacement.

4. The combination with a receptacle and cover, of a fastener comprising a headed pin secured to one of said parts, and a spring tongue member secured to the other part, there being a cavity in the latter part in which said tongue is housed, said tongue having a key slot to be engaged by the pin and normally arranged at an incline to the plane of movement of said pin, whereby said tongue is placed under tension when the pin is engaged therewith for holding the cover down tight on the receptacle, and a plate secured to the part having the cavity for covering said cavity, said plate having a slot for the passage of the pin.

5. The combination with a receptacle and cover, of a fastener comprising a headed pin member secured to one of said parts, and a spring tongue member secured to the other part, there being a cavity in the latter part in which said tongue is housed, said tongue having a key slot to be engaged by the pin and normally arranged at an incline to the plane of movement of said pin, whereby said tongue is placed under tension when the pin is engaged therewith for holding the cover down tight upon the receptacle, and a plate made integral with the tongue and folded upon the same for covering the cavity, said plate having a slot for the passage of the pin.

6. A cover fastener comprising a headed pin member, and a spring tongue member, having a key slot to be engaged by the pin, said tongue being normally inclined to the plane of movement of the pin whereby it is placed under tension when the pin is engaged therewith, and a spring retaining plate made integral with the tongue and folded back upon the same.

7. A cover fastener comprising a headed pin member, and a spring tongue member, having a key slot to be engaged by the pin, said tongue being normally inclined to the plane of movement of the pin whereby it is placed under tension when the pin is engaged therewith, and a cover plate made integral with the tongue and folded back upon the same, said cover plate being provided with a key slot opposite the key slot in the tongue member.

NELSON S. PECKENS.
